UNITED STATES PATENT OFFICE.

CHARLES A. RUSH, OF SAN FRANCISCO, CALIFORNIA.

VAPORIZER AND SEPARATOR.

992,260.

Specification of Letters Patent. Patented May 16, 1911.

Application filed May 27, 1908. Serial No. 435,244.

To all whom it may concern:

Be it known that I, CHARLES A. RUSH, a citizen of the United States, residing at San Francisco, in the county of San Francisco and State of California, have invented a new and useful Gasolene Vaporizer and Separator, of which the following is a specification in such full and clear terms as will enable those skilled in the art to construct and use 10 the same.

This invention relates to a gasolene vaporizer and separator, a portion of which may also be used as a steam separator either at the feed or at the exhaust end of a steam 15 engine.

An object of the invention is to prevent the gasolene from passing to the engine without being atomized, and to provide means for the complete atomization and vaporization 20 of that which does pass to the engine, where the device is used on an explosion engine.

Another object of the invention is to provide 25 means for regulating the supply of air that passes to the engine when the gasolene is being vaporized.

In the drawings in which the same numeral of reference is applied to the same part throughout, Figure 1 is a plan view of the 30 device partly in section through the separator and partly through the gasolene tank, Fig. 2 is a vertical central section through the complete device.

The numeral 1 is applied to the supply 35 pipe at the top of the tank 2, said supply pipe having a valve seat at its end. In the tank 2 there is a float 3 which moves up and down as the supply of gasolene increases or diminishes, guides 4 and 5 being provided 40 for the float and a guide 5' being provided for the needle valve 6 carried by the float. The bottom of the tank 2 is formed of a conical portion 7 and a cylindrical portion 8, the cylindrical portion extending out the 45 top of the tank 2 and being connected to the separating drum 9, to which latter the pipe leading to the engine is connected. At the bottom of the tank 2 there are three pipes 10 leading to a centrally placed valve 11 having the valve stem 12. Extending vertically 50 from this valve there is a pipe 13 which extends above the top of the gasolene in the tank, in order that the same may not overflow.

55 Secured within the conical portion of the bottom of the tank are three shell like leaves 14 each one indicated by a different

numeral 14 on Fig. 1, and of which two are shown below the revoluble separator 20 which are hinged to the bottom of the tank 60 at 15, and controlled by springs 16, said springs having one end secured to a pin 16' and the opposite end secured to the part of the hinge attached to the plate 14 for the purpose of holding the leaves closely together, as shown. The leaves are of such a shape that they may be moved considerably without producing a very large opening at their sides, the intention being to so shape them that when in the position shown in the 70 drawing almost all the air passing through the carbureter will pass near the mouth of the pipe 13. When the engine is running fast the tendency will be for it to require a larger amount of air and fuel and the pressure of the moving air on the leaves will cause them to open a small amount at their top, thus permitting the inlet of a larger supply of air and as the amount of air increases the amount of gas that will be drawn 80 from the tube by the passage of the air will increase.

Just below the separating drum 9, and at the top of the pipe 8 there is secured a spider 17 and in the pipe 18 leading to the engine 85 there is another spider 19. Journaled in the spiders is the revoluble separator 20 which is made up of a series of blades 21 the entire set forming a substantially spherical body carried by the shaft 22. This shaft 90 projects out of the pipe 18 at the elbow thereof, and it has secured to its end the pulley 23 for the purpose of driving the separator.

The separator drum is heart shape in 95 cross section and has a pipe 24 leading from its lowest portion to the tank 2, a check valve being placed in the pipe to prevent the possibility of any gasolene moving in that direction to the engine, from the tank. The motion of the separator will cause any liquid that may escape complete vaporization to be thrown out to the walls of the separator drum and as soon as it gets in the low portion thereof it will run back into the supply 100 tank 2. The check valve between the gasolene supply tank 2, and the drum 9 is intended to close when there is a lower pressure of air in the drum 9 than in the tank, but as soon as the pressures in the tank and drum 110 are equal the valve will open and permit any gasolene that may be thrown outwardly from the fan 21 to pass back into the gasolene tank. Such periods of equal pressure

will occur often enough to permit the return of any gasoline that may pass over into the drum 9 from the feed pipe 13.

Having thus described my invention what I claim as new and desire to secure by Letters Patent of the United States is as follows:

1. In a gasoline vaporizer, the combination of a tank having an air channel there-through, a gasoline supply pipe leading from the bottom of the tank to a point near the center of the air channel, overlapping leaves in said air channel adapted to regulate the amount of air passing therethrough, a rotary separator in the air channel, and means to return unvaporized gasoline to the supply tank, as set forth.

2. In a gasoline vaporizer, the combination of a gasoline supply tank having an air channel therethrough, means to maintain the

gasoline therein at substantially the same level at all times, a gasoline pipe leading to a place near the center of the air channel, spring held overlapping leaves in the air channel and adapted to restrict the flow of air therein to a circle of smaller diameter than the diameter of the air channel, a separator drum in the air channel, a rotary separator therein, and means to return unvaporized gasoline to the supply tank, as set forth.

In testimony whereof I have set my hand this 16th day of May A. D. 1908, in the presence of the two subscribed witnesses.

CHARLES A. RUSH.
